CLAUDE A. BULKELEY, OF KENMORE, NEW YORK, ASSIGNOR TO NIAGARA BLOWER COMPANY, OF BUFFALO, NEW YORK, A CORPORATION OF NEW YORK

CLIP

Application filed August 5, 1930. Serial No. 473,147.

This invention relates to a clip and more particularly to a clip which is adapted to be applied to the edge of a hide or the like and to be caught in a stretching frame of the general type shown in my co-pending application, Serial No. 473,146 filed of even date herewith.

In such a frame the hide is supported on a sheet metal face plate having its entire face provided with a series of perforations, by 10 a plurality of clips embodying the present invention, these clips gripping the edges of the hide and each clip having means to catch the clip in one of the perforations so that the hide can be held taut from the sheet metal face plate.

The principal object of this invention is to provide a spring connection between that portion of the clip which grips the hide and that portion of the clip which is hooked into 20 the perforated plate and which also carries the finger piece or handle by means of which the hide is drawn taut. By the provision of such a spring between these elements the danger of tearing the hide is practically eliminated since should the operator exert too much force in drawing the hide taut the spring will yield and prevent tearing of the hide. Furthermore, after the hide has been 25 stretched on the frame by means of clips embodying the present invention the shrinkage of the hide while drying will not tear the hide at its places of connection with the clips because of the spring being interposed between the hide gripping member and the 30 member which is secured to the sheet metal face plate of the frame.

A further object is to provide such a clip 40 which can be manipulated entirely with one hand and can be quickly and easily used in either stretching the hide in place upon a stretching frame or in removing it therefrom.

A still further object is to provide such a clip which reliably grips the hide and also 45 is reliably held in position on the stretching frame so that there is no danger of the hide becoming loose, especially as it shrinks and its tension upon the clips increases.

Other purposes are to provide such a clip 50 which is of simple and inexpensive construc-

tion, which is durable and is reliable in operation and will not get out of order under severe and constant use.

In the accompanying drawings:

Fig. 1 is a side elevation of a clip embodying the present invention, showing the same holding a hide or the like upon a stretching frame. 55

Fig. 2 is a top plan view thereof.

Fig. 3 is a longitudinal section taken on line 3—3, Fig. 2. 60

Fig. 4 is a transverse section taken on line 4—4, Fig. 1.

Similar characters of reference indicate like parts in each of the several figures of the drawings. 65

The frame in connection with which the present invention is adapted to be used can be of any usual and well known construction, the stretching frame which I prefer for this purpose forming the subject matter of my co-pending application, Ser. No. 473,146, filed Aug. 5, 1930. In general, such a frame consists of a sheet metal face plate 5 which is reinforced at its edges by angle irons 6 which can be secured by means of rivets 7 or in any other suitable manner. Substantially the entire surface of the face plate 5 is perforated to provide holes 8, these holes being of comparatively small size and large in number so that when the hide 9 is gripped at its edges by the clip embodying the present invention the clip can be caught in any one of the adjacent holes 8 in the face plate 5 and hold the hide 9 taut. 70

The clip in general comprises a gripping part which is adapted to grip the hide and is indicated generally at 10 and a second part, indicated generally at 11, which is slidably secured to the gripping part and is formed with the finger for engaging the holes 8 in the face plate and also with a handle by which the operator can pull the gripped hide taut. A spring is interposed between these parts. 75

The part 10 which is adapted to grip the hide is made of sheet metal and consists of a tongue 12 having a reversely formed lip 13 at its front end and wings 14 at the opposite sides of its front end which wings rise from 80 90 95 100

opposite sides of the tongue. The wings 14 are each indented as indicated at 15 to receive the edge of the leather hide 9 and the reversely formed lip 13 forms a lower jaw for gripping the edge of this hide. The upper jaw 16 is movable and consists of a reversely formed cam portion 17 which is milled or roughened on its underside and a handle 18 which extends rearwardly. The upper jaw is pivoted 10 to the side wings 14 as indicated at 19, this pivoted being located so that the cam portion 17 swings underneath the pivotal connection. The cam portion 17 is so formed that upon downward movement of the handle 18 the 15 cam portion 17 is brought against the lower jaw or reversely formed portion 13, the cam portion 17 traveling forwardly in this movement. It is apparent that with this form of cam portion 17 the tension of the hide tends 20 to draw the cam portion 17 into firmer engagement with the hide so that increased tension of the hide instead of tending to pull the hide free from the clip tends to draw its jaws more firmly in engagement therewith. 25 The member 11 includes a lower horizontal portion 20 upon which the tongue 12 slides longitudinally and to guide the tongue 12 in its sliding movement the lower part 20 is formed to provide two pairs of lips 21 which 30 engage over the opposite side edges of the tongue 12 and hold the tongue 12 against displacement. At its rear end the lower part 20 is bent upwardly and is formed to provide a handle 22 which can be of any suitable form 35 to permit of the clip being readily grasped by the finger of the operator. The lower part 20 in which the tongue 12 slides also has struck downwardly therefrom a reversely formed finger 24, this finger being of sufficiently small size so that it can enter any of the holes 8 in the sheet metal face plate of the stretching frame. 40 Interposed between the members 10 and 11 is a helical tension spring 25. This spring is 45 secured to the member 10 by means of a pin 26 which is carried by and extends between the wings 14 of the part 10 and at its rear end this spring is secured to a lip 27 which is struck forwardly from the handle 22 of the 50 part 11. This spring when embodied in a clip for stretching hides preferably begins to open up at about fifteen pounds and it will therefore be apparent that if the operator pulls upon the handle 22 in excess of this 55 pressure in stretching the hide the spring 25 will give and the excess pressure will not be exerted upon the edge of the hide 9 which is held between the jaws 17 and 13 of the part 10. It is also apparent that the hide is 60 stretched and the finger 24 of each clip caught in one of the holes 8 of the sheet metal face plate 5. Should the shrinkage of the hide exceed the tension of any one of the springs 25, the spring 25 will yield permitting the jaws 65 17 and 13 and tongue 12 to be moved under

this tension and thereby avoid tearing the hide.

In applying clips embodying the present invention the operator lifts the handle 18 which moves the roughened cam portion 17 away from the lower jaw 13 and thereby permits the edge of the hide 9 to be inserted between the jaw 13 and the cam portion 17, as indicated in Fig. 1. The operator then presses the handle 18 downwardly which moves the roughened cam portion 17 downwardly and forwardly and compresses the edge of the hide between the cam portion 17 and the lower jaw 13. Since any tension upon the hide 9 will tend to draw the cam portion 17 into firmer engagement with its margin the hide is reliably and firmly secured between the jaws 17 and 13 and will not become loose. The operator through the handle 22 then draws each of the clips outwardly so as to draw the hide 9 taut upon the perforated plate 5. In doing so he catches the hook 24 of each of the clips in the proper opening 8 to hold the hide in this taut condition upon the perforated face plate. It is apparent that if he exerts too much pressure, that is in excess of about fifteen pounds, the spring 25 will give and thereby avoid tearing of the hide. If after the hide is stretched in position on the perforated plate 5 its tension in shrinking becomes excessive, the springs 25 will again yield, permit the clip to expand and again avoid tearing of the hide. 90

Another further decided advantage in this clip is that by this automatic spring tension being maintained at all times on the hide while it is drying, more tension can safely be put on the hide at the time it is stretched, and all the tension which the hide will safely stand is maintained at all times during its drying. This maintenance of a maximum tension on the hide results in an increase of footage per hide since each hide is stretched its maximum extent. 100

In clips heretofore designed without spring tension operators put very little tension on the green hide since if they did the shrinkage would have been liable to cause tearing. With the present clip a maximum of allowable tension, of say fifteen pounds, is put on each clip at the start and if the hide shrinks the spring gives, allowing for shrinkage of the hide without tearing. 110

In actual practice, by using a spring tension scale in conjunction with clips as heretofore designed for this purpose it was found that many clips had a tension on the hide at the start before drying of only four to five pounds and some of them having as high as twenty to twenty-five pounds. After the hide was dried the tension varied all the way from nothing to as high as forty-seven pounds, this being due, of course, to the fact that there was no give to these clips. It has been found that it is very easy for an opera- 120 125 130

tor to tell when the spring begins to give, or in other words when he has the required tension on the hide, for he can feel the spring give. Thus he automatically places the correct tension of say fifteen pounds on each hide.

From the foregoing it is apparent that the present invention provides a clip for this purpose which is very simple and inexpensive, easily manipulated, durable and will not get out of order under constant use, at the same time the spring means provided in the clip prevent tearing of the hide either while it is being drawn taut or when it shrinks in drying, insures the maximum tension being maintained on the hide during drying thereby providing for increased footage of the hide, and insures an even tension being maintained on the hide all around.

I claim as my invention:

1. A fastener for holding hides or the like in a stretched condition on a frame, comprising a part having a handle and being adapted to be removably secured to said frame, a second part adapted to be removably secured to said hide and spring tension means between said parts.

2. A fastener for holding hides or the like in a stretched condition on a frame, comprising two parts and spring tension means connecting said parts, one of said parts including a pair of jaws adapted to be applied to said hide and the other part including a handle and a hook on its underside, said hook being adapted to be engaged with said frame.

3. A fastener for holding hides or the like in a stretched condition on a frame, comprising a part having a lower flat portion adapted to be secured to said frame, a handle and reversely formed lips at the sides of said lower flat portion, a second part having a tongue slidably received between the lips of said first part and having means for gripping the edges of said hide and a spring connecting said parts and yieldingly holding said parts together.

4. A fastener for holding hides or the like in a stretched condition on a frame, comprising a part having a lower flat portion having a depending finger by which it is adapted to be secured to said frame, a handle and reversely formed lips at the sides of said lower flat portion, a second part including a tongue slidably received between the said lips of said first part and formed at its front end to provide a reversely formed lower jaw and upstanding side wings and a movable jaw pivoted between said upstanding wings and movable toward said lower jaw to grip the edge of the hide therebetween and spring tension means tending to draw said parts together.

5. A fastener for holding hides or the like in a stretched condition on a frame having a plurality of holes in substantially its entire

area, comprising a part having a lower flat portion having a depending finger adapted to be caught in one of said holes, a handle rising from the rear end of said lower flat portion and reversely formed lips at the sides of said lower flat portion, a second part including a tongue slidably secured between the said lips of said first part and formed to provide a reversely formed lower jaw at its front end and upstanding side wings, a movable jaw pivoted between said wings and having a rearwardly extending handle upon the depression of which said upper jaw is moved toward said lower jaw to grip the edge of the hide therebetween and a cross pin between said wings and a tension spring connecting said cross pin and said handle on said first part, said spring yieldingly holding said parts together and opening up on a tension of about fifteen pounds.

In testimony whereof I hereby affix my signature.
